(57) **CLAIM**

The ornamental design for a foldable electric kettle, as shown and described.

DESCRIPTION

FIG. 1 is a top, front, right perspective view of a first embodiment of a foldable electric kettle showing my new design;

FIG. 2 is a bottom, rear, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded top, front, right perspective view of the foldable electric kettle of FIG. 1;

FIG. 10 is a top, front, right perspective view of the foldable electric kettle of FIG. 1, where the foldable electric kettle is in a folded state;

FIG. 11 is a top, front, right perspective view of a second embodiment of the foldable electric kettle showing my new design;

FIG. 12 is a bottom, rear, left perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an exploded top, front, right perspective view of the foldable electric kettle of FIG. 11; and,

FIG. 20 is a top, front, right perspective view of the foldable electric kettle of FIG. 11, where the foldable electric kettle is in a folded state.

(Continued)

The broken lines in the drawings depict portions of the foldable electric kettle that form no part of the claimed design.
